UNITED STATES PATENT OFFICE.

HAROLD V. ATWELL, OF WHITING, INDIANA, ASSIGNOR TO STANDARD OIL COMPANY,
OF WHITING, INDIANA, A CORPORATION OF INDIANA.

SEAL.

Application filed May 24, 1924. Serial No. 715,765.

To all whom it may concern:

Be it known that I, HAROLD V. ATWELL, a citizen of the United States, residing at Whiting, in the county of Lake and State of Indiana, have invented a new and useful Improvement in Seals, of which the following is a specification.

This invention relates to improvements in seals or vent valves, more particularly as applied to the vent pipes from storage tanks containing gasoline or other similar volatile liquids. It will be fully understood in the following description, illustrated in the accompanying drawings, in which:

15 Figure 1 is a plan view of a valve embodying the invention;

Fig. 2 is a vertical sectional view therethrough, and

20 Fig. 3 is a side elevation of the valve of Fig. 1.

Referring more particularly to the drawings, the numeral 5 indicates an upturned end of a vent pipe, which is brought down, ordinarily from a considerable elevation, for example, the vapor space of a gasoline storage tank. To the vent pipe 5 is connected a short vertical pipe section, which projects into a pan or receptacle 7 containing liquid. The pipe section 6 projects slightly above 30 the liquid level in the pan 7.

Suitably pivoted in the pan 7, for example, on a rod 8 journaled in its sides, is an inverted cup 9, suitably of elongated rectangular section. The rod 8 passes through substantially the center of gravity of the cup 9, which is so constructed that it is substantially balanced when the portion on one side of the pivot rod 8 is longer than the other. This may be accomplished, for example, by means of a suitable weight 10 secured to the short side of the cup. Thus, as shown in the drawings, the portion of the cup on the right of the pivot rod 8 is somewhat longer than the portion on the left. As a result of the unsymmetrical mounting of the inverted cup 9, the center of pressure, which is above the pipe 6, is at one side of the pivot mounting. As a result of this construction, when the pressure within the vent pipe 5 exceeds a predetermined amount, one side of the inverted cup 9 (in the form shown, the right side) is caused to rise, the other side being forced deeper into the liquid, until the side being raised 50 emerges above the liquid level and permits

escape of gas or vapors. Similarly, when the pressure within the vent pipe is less than that of the external atmosphere by a predetermined amount, the right side of the inverted cup is drawn downwardly, the other side emerging from the liquid and permitting ingress of air.

The relative amounts of difference in pressure required to operate the seal are controlled by floats 11 and 12, on the ends thereof. These floats determine the relative force required to immerse the respective ends of the seal in the liquid. For example, in the form shown, a smaller float is employed on the right side than the float 12 on the left side. With this form of construction, a less difference in pressure will be required to force the right end to immerse (on reduced pressure within the vent) than that required to cause the left end to 75 immerse (on high pressure in the vent pipe).

Suitable means may be provided, if desired, for damping any rocking movement of the inverted cup member in its operation. For example, perforated partition members 13 may be provided at each end of the cup, partitioning off a portion of the ends of the cup, and providing enclosed spaces 14. As either end of the cup is immersed, water passes through the perforation in the corresponding partition member 13 into the space 14. On the rise of the immersed end of the cup, more or less of the sealing liquid is retained in the space 14, flowing out slowly through the perforations in the partition. Any tendency of the cup to rock is thereby materially damped.

Although my invention has been shown in connection with a specific embodiment thereof, it is not intended that the specific details of this embodiment shall be regarded as limiting the scope of the invention.

I claim:

1. A seal comprising an open conduit member communicating with a vapor space, a pan surrounding said conduit member and adapted to contain a liquid, an inverted cup over said conduit member and having its sides immersed in the liquid in the pan, said cup having its center of pressure offset from its center of gravity, and means for pivotally supporting said cup at substantially its center of gravity.

2. A seal comprising an open conduit

member communicating with a vapor space, a pan surrounding said conduit member and adapted to contain a liquid, an inverted cup over said conduit member and having its sides immersed in the liquid in the pan, said cup having its center of pressure offset from its center of gravity, means for pivotally supporting said cup at substantially its center of gravity, and means for determining the differences in pressure required to further immerse its respective ends.

3. A seal comprising an open conduit member communicating with a vapor space, a pan surrounding said conduit member and adapted to contain a liquid, an inverted cup over said conduit member and having its sides immersed in the liquid in the pan, said

cup having its center of pressure offset from its center of gravity, means for pivotally supporting said cup at substantially its center of gravity, and floats secured to the ends of said cup.

4. A seal comprising an open conduit member communicating with a vapor space, a pan surrounding said conduit member and adapted to contain a liquid, an inverted cup over said conduit member and having its center of pressure offset from its center of gravity, means for pivotally supporting said cup at substantially its center of gravity, and means for damping rocking movement of the cup.

HAROLD V. ATWELL.
